A. BULL.
ALARM CLOCK.
FILED JAN. 11, 1922.

Inventor

AndersBull.

UNITED STATES PATENT OFFICE.

ANDERS BULL, OF CHICAGO, ILLINOIS.

ALARM CLOCK.

Application filed January 11, 1922. Serial No. 528,498.

To all whom it may concern:

Be it known that I, ANDERS BULL, a citizen of the United States, residing at 919 Leland Avenue, in the city of Chicago, county of Cook, and State of Illinois, have invented a new and useful Alarm Clock, of which the following is a specification.

My invention has for its object to provide an inexpensive and convenient means for notifying a person of the expiration of a predetermined time period and may also, in part, be applied to alarm clocks of the ordinary type with a view to simplifying its manipulation and construction with a consequent reduction of its cost.

The clock described in this specification may be used in the kitchen for cooking and baking, in the laboratory for indicating the completion of chemical and physical processes, for photographic work, in the plating room, factory, office, and for a great variety of other purposes. For such use, the ordinary alarm clock is unsuited as the operations necessary to time the alarm signal are too cumbersome: the time at which the signal shall be sounded must be figured out, the alarm pointer carefully set, two keys must be wound, and the alarm stop released.

In my improved design, these operations have been much simplified. All that is needed is to set a pointer and to wind one key. Upon the expiration of the time period indicated by the pointer an alarm signal is sounded and the clock stops. Though the clock may be built for any total time period desired there is comparatively little need for an alarm signal to be timed more than an hour in advance, so the clock has been designed primarily with this end in view. To this purpose one pointer only is required and the construction thus simplified. The dial is divided in 60 parts as usual, each division representing one minute, and inscribed at suitable intervals with numerals indicating the total number of divisions counting backwards from the zero mark, the term "backwards" being used for a direction opposite to the one in which the pointer is impelled by the works.

Another important simplification is effected through a special arrangement of the clock gears permitting the winding of both time- and alarm works to be done in a single operation. Provisions are, moreover, made so that the main spring can never

fully relax, by virtue of which half a turn of the winding key is ample to run the clock for an hour and to sound the alarm signal.

I attain these objects by means of the arrangement illustrated in the accompanying drawings representing part of the movement of a clock. Fig. 1 is a face view of the works showing a portion of the dial; Fig. 2 is a section taken on line A—A in Fig. 1; and Fig. 3 is a zig-zag section taken on line B—C in Fig. 2, similar numerals referring to similar parts throughout the several views.

Figs. 2 and 3 show the main spring 1, fastened at one end to the spring carriage or capsule 2 and at the other to the shaft 3 which is pivoted in the bushing 4 and frame 5 and is rigidly connected with the main time gear 6 while the capsule is rigidly connected with the ratchet 7 and the bushing 4. In a groove formed by the ratchet and a shoulder on the bushing is loosely mounted the main alarm gear 8.

By winding the key 9 which is fitted into the bushing, the capsule is turned in a clockwise direction as viewed in Fig. 3 and the spring is coiled up, a tendency being thereby imparted to the main time gear 6 to rotate in the same direction, as indicated by the arrow to the left in Fig. 3.

On releasing the key, the spring is prevented from recoiling by the pawl 10 engaging the ratchet 7. The pawl is fastened to the main alarm gear 8 which operates the clapper 11 through gears 12, 13, 14, and the star wheel 15. The spring acting through the ratchet and pawl strives to rotate gear 8 in the opposite direction of that of gear 6, as indicated by the arrow to the right in Fig. 3; however, no such movement can take place until the clapper has been released through the alarm control mechanism.

The main time gear 6 meshes with the cog-wheel of the pointer gear 16 the hub of which is frictionally connected with its pivot 17 in the customary way, by means of friction washers 18. Its movement is controlled by the escapement acting through gears 19, 20, and several others. These other gears as well as the escapement are arranged in a similar way as in the ordinary alarm clock for which reason they have been omitted from the diagrams.

Fixed to the dial end of the pivot 17 (Figs. 1 and 2) is a cam 21 which, when the pointer

- approaches the zero mark on the dial 23 (coinciding with the 60 mark), engages a pin 24 on the lever 25, forcing the latter to the right against the pressure of a spring 26.
- 5 The extreme end of this lever is bent so as to catch the pointed end of another lever 27 which is secured to the pivot of the clapper 11, thereby arresting its movement. On the pointer reaching the zero mark, however, the lever 25 has been pushed far enough to the right to release the clapper and the alarm signal is sounded.

At this juncture, the left hand edge of the oval shaped hole 28 in the lever will all but 15 make contact with the pivot 17, therefore the pointer can only be moved a fraction of a division beyond the zero mark. Similarly, in setting the pointer by turning the button 29, the pointer cannot be turned backwards 20 more than one revolution, corresponding to the 60 mark on the dial, because the cam, now striking the pin 24 from the right while the right hand edge of the hole 28 is in contact with the pivot, will again stop it.

25 To the rim of the capsule 2 (Figs. 2 and 3) is riveted an angular piece 30 engaging another piece 31 on the main time gear 6. These two pieces serve to limit the motion 30 of the capsule relative to said gear to about one revolution and thus prevent the spring both from being overstressed and from uncoiling beyond a certain measure. The spring power is thus kept within fixed limits sufficient to operate both time- and 35 alarm works satisfactorily. 32 are posts for keeping the two parts of the frame together.

In operating the clock, if it be for inst. 40 desired to have the signal sounded at the end of 15 minutes, the pointer is set back by hand by 15 divisions on the dial. The key 9 is then given a quarter of a turn or more, according as a short or long signal is wanted, and the clock started. As the slightest setting back of the pointer immediately 45 causes the clapper to be arrested, the alarm gears cannot turn, so the spring power at the start is consumed in moving the time gears only, the pointer moving over the dial in the usual direction. At the end of 15 50 minutes the pointer will have reached the zero mark, the clapper is set free, and the remainder of the spring power stored up in

winding the key is consumed in striking the alarm bell, after which the clock automatically stops.

55

The gear arrangement above described is also adaptable to ordinary alarm clocks, means being in this case provided for limiting the duration of the alarm signal, as in clocks for "spasmodic alarm," to insure that 60 only a part of the spring power is consumed in ringing the bell.

I claim:

1. In alarm clocks having one main spring 65 for driving the time- and alarm mechanisms, the combination of a stop connected with one end of the spring, with a catch connected with the other end, said stop and catch co-operating to limit the rotational displacement of the spring ends relative to each 70 other for the purpose set forth.

2. In clocks comprising a time- and alarm mechanism, the combination of a dial reading from zero to 60 minutes, and a pointer fixedly connected through its pivot with its 75 button and adapted to be moved by the time mechanism over said dial, with means operated through said pivot for arresting the alarm mechanism at the slightest turning back of the button after the pointer has been 80 brought into its zero position.

3. In alarm clocks, the combination of a dial reading from zero to 60 minutes, and a pointer fixedly connected through its pivot with its button, with means operated through 85 the pointer pivot limiting the scope of motion of the pointer and arresting the alarm mechanism at the slightest turning back of the button whenever the pointer is in its zero position.

90

4. In alarm clocks, the combination of a single main spring for driving the time- and alarm mechanisms, a dial reading from zero to 60 minutes and a pointer for said dial fixedly connected through its pivot with its 95 button, with means for keeping the spring deflection within fixed limits, a member operated through the pointer pivot for limiting the scope of motion of the pointer, and means cooperating with said member for arresting the alarm mechanism at the slightest turning back of the button whenever the pointer is in its zero position.

100

ANDERS BULL.
